(57) **CLAIM**

The ornamental design for a holster strap swivel mount, as shown and described.

DESCRIPTION

FIG. 1 is a front perspective view of the holster strap swivel mount design in the environment of a holster support plate and with a leg strap plate extending between features thereof;

FIG. 2 is a front perspective view of the holster strap swivel mount design;

FIG. 3 is a rear perspective view of the holster strap swivel mount design;

FIG. 4 is a front elevation view of the holster strap swivel mount design;

FIG. 5 is a rear elevation view of the holster strap swivel mount design;

FIG. 6 is a right side elevation view of the holster strap swivel mount design;

FIG. 7 is a left side elevation view of the holster strap swivel mount design;

FIG. 8 is a top plan view of the holster strap swivel mount design;

FIG. 9 is a bottom plan view of the holster strap swivel mount design;

FIG. 10 is a front perspective view of an alternative position of the holster strap swivel mount design;

FIG. 11 is a front perspective view of a further alternative position of the holster strap swivel mount design;

FIG. 12 is a front perspective exploded view of the holster strap swivel mount design; and,

FIG. 13 is a rear perspective exploded view of the holster strap swivel mount design.

The broken lines in the figures showing the environment of a holster support plate and leg strap plate form no part of the claimed design.
